UNITED STATES PATENT OFFICE.

ERNST KARL ALEXANDER BAUMANN AND FRIEDRICH WILHELM SEYBOTH, OF ZWICKAU, GERMANY.

SUCTION-CLEANING APPARATUS.

No. 878,109.

Specification of Letters Patent.

Patented Feb. 4, 1908.

Application filed March 21, 1907. Serial No. 363,537.

To all whom it may concern:

Be it known that we, ERNST KARL ALEXANDER BAUMANN and FRIEDRICH WILHELM SEYBOTH, subjects of the Emperor of Germany, and residents of Zwickau, Saxony, Germany, have invented a certain new and useful Improvement in Suction Cleaning Apparatus, of which the following is a specification.

10 This invention relates to suction cleaning apparatus of the kind in which manually actuated bellows are employed to produce the suction.

The invention has for its primary object 15 to provide a construction of such apparatus which is made of wood, both cheap and light and can be used both as a dust extractor and as an article of furniture such as a bench, stool, chair or table, the dust collector being 20 arranged beneath the hinged seat.

A further object is to provide in such apparatus an improved dust collecting box whereby all the dust will be removed from the air before it reaches the bellows.

25 The invention is illustrated in the accompanying drawing in which

Figure 1 is a part vertical section part elevation showing a combined dust extractor and stool. Fig. 2 is a part section showing 30 the improved dust collecting box.

As shown in Fig. 1, the suction tube 1 is connected with the dust collecting chamber 2 formed by the frame 3 and the bellows 4. The bellows 4 is double acting with two compartments 5, 6, the suction valves of which are connected with the dust collecting chamber 2 by pipes 7 and 8, while the pressure valves are directly connected with the atmosphere by means of pipes 9, 10. This representation is diagrammatic only. In practice instead of pipes passages would be cut in the wooden frame. The bellows may be actuated continuously by a treadle or handle 11, and the helical spring 12. On upward 45 movement of the treadle in the direction of the arrow shown in full lines air is sucked into the compartment 6 of the bellows out of the collecting chamber 2 through the pipe or passage 8. There is thus produced a vacuum 50 in the said chamber 2, so that the outer air passes through the tube 1 into the chamber 2. The dust carried by the air falls by the action of gravity on the bottom of the chamber 2. At the same time air is forced out of 55 the compartment 5 of the bellows through

the pipe 9 into the atmosphere. The current is shown by the arrows in full lines. On pressing down the treadle in the direction of the arrow drawn in dotted lines the current is reversed, as shown by the arrows drawn in dotted lines. The air sucked from the chamber 2 passes through the pipe 7 into the compartment 5 of the bellows, while at the same time the air in the compartment 6 escapes from the valve through the opening 60 10 into the atmosphere.

In the embodiment shown in Fig. 2 there is arranged in the dust collecting chamber 2 a removable dust collecting box which enables the air to be entirely freed from dust. In 70 the lower part which is not shown in section is the suction apparatus, which for instance may consist in known manner of double acting bellows actuated by a treadle 11. The air sucked up which passes through the suction valve 13 into the bellows and thence again into the atmosphere must on entering the suction valve be already freed from dust. Into the dust collecting box passes the dust laden air sucked up through the tube 1 flowing 75 downwardly. It strikes the inclined bottom surface of the collecting box and passes in the direction of the arrow 14 downwardly therein. In consequence of the large cross sectional area of the collecting 80 box the movement of the air is already retarded so that the greatest part of the dust which slides downwardly on account of its weight settles in the corner 15 of the dust collecting box which is provided with an inclined base. Should by the slight movement 85 of the air any dust particles be carried by it in the direction of the arrow 16, these are caught by the overturned edges of the box which form a circular arch, so that they receive a further movement in the direction of the arrow 17, again descend on account of their weight and are prevented from leaving the box. A similar operation is undergone 90 by those dust particles which are moved on account of the circulation of the air in the direction of the arrows 18 and 19. They fall first into the upper corner of the inclined bottom and slide along the same back into the corner 15. The air freed from dust now 95 passes in the direction of the arrows 20 and 21 out of the dust collecting box, in order to pass in the direction of the arrows 25 and 26 to the suction valve. In order now to retain 100 any fine meal-like dust particles which may 105 110

still be contained in the air, the upper opening of the dust collecting box is not free but is closed by a thin filter cloth 23 which is suitably clamped to the cover 3 and weighted at its edge with a frame 24 resting on the circular arch as shown. Through this filter 23 the air must pass so that also the last and finest particles of dust are caught thereby. As the air before its passage through the filter is almost entirely freed from dust the filter will not be choked in a short time as happens when cloth filters alone are employed, so that the resistance of the filter will always remain small and effective sucking up of the dust will be possible. The dust collecting box is desirably provided at the lowest part of the same, at the corner 15, with an opening 27 to enable the dust to be readily removed.

Having now described our invention what we claim and desire to secure by Letters Patent of the United States is:—

1. The improved suction cleaning apparatus, comprising, in combination, a stool having a hinged seat, a dust collecting chamber having a downwardly sloping base disposed

below said seat, and manually actuated double-acting bellows fitted below said chamber and having passages for receiving inflowing air and discharging the air, substantially as described. 30

2. The improved suction cleaning apparatus, comprising, in combination, a stool having a hinged seat, a dust collecting box located below said seat and having a downwardly sloping base and a roof formed with an annular arch, a filter cloth closing the opening of the box, a frame stretching said filter cloth, said frame resting on said arched roof, and manually actuated double-acting 35 bellows fitted below said box and having passages for receiving inflowing air and discharging the air, substantially as described. 40

In testimony whereof we have signed our names to this specification in the presence of 45 two subscribing witnesses.

ERNST KARL ALEXANDER BAUMANN.
FRIEDRICH WILHELM SEYBOTH.
